(57) **CLAIM**

The ornamental design for a refrigerator, as shown and described.

DESCRIPTION

FIG. 1 is a front perspective view of the refrigerator showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 a partial enlarged view of the area '8' as identified in FIG. 1;

FIG. 9 a partial enlarged view of the area '9' as identified in FIG. 1; and,

FIG. 10 is a front perspective view showing the state of use that the front door panels have been separated. The broken lines depict portions of the refrigerator that form no part of the claimed design.
